UNITED STATES PATENT OFFICE.

SCOTT H. PERKY, OF ITHACA, NEW YORK.

MACHINE FOR MAKING CELLULAR BISCUITS.

1,071,459.

Specification of Letters Patent. Patented Aug. 26, 1913.

Application filed August 19, 1908. Serial No. 449,203.

To all whom it may concern:

Be it known that I, SCOTT H. PERKY, a citizen of the United States, resident of Ithaca, in the county of Tompkins and 5 State of New York, have made a certain new and useful Invention in Machines for Making Cellular Biscuits; and I declare the following to be a full, clear, and exact description of the same, such as will enable 10 others skilled in the art to which it appertains to make and use the invention, reference being had to the accompanying drawings, and to letters or figures of reference marked thereon, which form a part of this 15 specification.

Figure 1 is a section of the machine, taken on the line 1—1 Fig. 4, with the parts thereof engaged. Fig. 2 is a side view with the parts separated. Fig. 3 is a plan view of 20 the base of the machine with the forming plate shown in dotted lines. Fig. 4 is a section of the machine on the line 4—4 Fig. 25. Fig. 5 is a detail perspective view of one of the sections. Fig. 6 is a detail cross section of the discharging plate.

The invention relates to a form of food designed to be made of grain, and it consists in the novel construction and combinations of parts constituting the forming 30 devices, and in the resulting article, as hereinafter set forth.

In the accompanying drawings, illustrating the invention, the letter *a*, designates a molding or forming plate having extending 35 from its base *b*, a number of conical or pyramidal projections *c*. These projections have short vertical bearings *s*, at their large ends and taper each to a dull point or nearly so, and they have a chequered arrangement 40 on the base, being not quite contiguous to each other along diagonal lines, and having base interspaces or intervals *d*, slightly larger than their base diameter, intervening, as shown in the drawings. This 45 plate is designed to mold or form one face of the article. A similar molding or forming plate *e*, also provided with similarly arranged projections *f*, of similar form to those on plate *a*, is provided to form the 50 other face of the article. While the projections *f*, have a chequered arrangement similar to that of the projections *b*, on plate *a*, their arrangement is such as to effect an 55 alternation or interposition of the projections *f*, in the intervals between the projections *c*. These molding or forming plates

may conveniently be made in sections *s'*, secured in a frame *t*, by means of suitable fastenings, such as the wedges indicated at *w*. Around each base of these two plates *a*, and *e*, extends a shoulder *g*, which serves as a bearing for the side wall or inclosing piece *h*, which is designed to inclose and give shape to the material in a circumferential manner. This inclosing wall may be 60 made in one piece or in several pieces, and the breadth of its wall is determined by the altitude of a projection from its base, being a little greater than the distance between the bearings of the two plates and said altitude. This wall serves not only to limit the 65 circumferential boundary of the article, but also its thickness, and to that end operates as a stop to prevent the projections of one molding plate from coming in contact with 70 the base of the opposite molding plate. 75

On the base of each forming plate rests a perforated discharging plate *z*. This plate is comparatively thin, being equal to the depth of the bearings *s*, of the projections, and its 80 perforations *k*, are of sufficient size to allow its intermediate portions *n*, to rest squarely on the base when said perforations engage the projections of the forming plate. These 85 discharging plates are provided with extensions *p*, projecting laterally and serving to engage the inclosing wall piece *h*. In order to operate these plates the material in sufficiently plastic condition is placed in proper 90 quantity upon the ends of the projections of one of these molding plates, which is engaged by the inclosing wall piece *h*. Then the other molding plate is brought into 95 forcible contact with the material, and is pressed into engaging position so that its shoulder *g*, bears against the margin of the wall piece. In the discharge of the formed 100 article the perforated plates are kept in engagement with the inclosing wall *h*, and the molding plates withdrawn, then the perforated plates are removed and the formed article can be taken from the wall piece *h*, and removed to a pan for baking. As the 105 shell form of this article is quite thin it can be readily baked hard and crisp, and in this condition is designed to form an article of food which will bear transportation well and will form a desirable commodity for general distribution. While this article of food has superficially somewhat the appearance of a waffle, it is essentially different in 110 that the projections are not solid but are

shell-like, being made hollow, in order to give the article an especially light and crisp character.

Having thus described my invention, what I claim as new and desire to secure by Letters Patent is:

1. A machine for making cellular biscuits, having opposite parallel-movable forming plates, each having a base and extending therefrom tapering projections having a chequered arrangement on said base, and adapted to project into the interspace surrounding the projections of the opposite plate past the middle portions of the latter projections, inclosing side walls and means for stopping the projections from coming into contact, parallel-motion guides and a thin perforated discharging plate on the

base of each forming plate and movable toward the free ends of the tapering projections.

2. In a machine for making cellular biscuit, opposite parallel-movable forming plates each having a base, and extending therefrom tapering projections having a chequered arrangement on said base vertical bearings, inclosing walls, and removable perforated discharging plates on the base of each forming plate, engaging said vertical bearings.

In testimony whereof I affix my signature, in presence of two witnesses.

SCOTT H. PERKY.
